BUTTON BACK

Erik A. Nygard, Woonsocket, R. I.

Application October 6, 1945, Serial No. 620,764

3 Claims. (Cl. 24—105)

1

This invention relates to a device usually referred to as a button back for securing lapel buttons or the like in position.

The usual button back is secured to the stud of a lapel button by there being threads upon the stud and threads on the walls of an opening in the button back so as to receive the same. The threads are usually fine and a considerable amount of rotation is necessary for securing the parts in position. Further, there is by this arrangement no lock for the parts and the resiliency of a fabric to apply a tension on the parts is relied upon to hold them in position.

One of the objects of this invention is to provide a button back which may be forced into position without rotation and which will be maintained in such position securely.

Another object of this invention is to provide a button back which cannot be released by straight axial nonrotative movement but which will require relative rotation with reference to the stud in order to release it.

Another object of this invention is to provide a button back which may be easily and quickly moved along the major portion of the stud but which will require some relative rotation for finally securing the same into position.

Another object of the invention is to provide a button back which may be easily and quickly used for mounting the button upon cards for retail sales.

With these and other objects in view, the invention consists of certain novel features of construction, as will be more fully described and particularly pointed out in the appended claims.

In the accompanying drawings:

Fig. 1 is a perspective view of a button with my button back in position thereon;

Fig. 2 is an exploded perspective view of the various parts of the button and its back;

Fig. 3 is a diametric sectional view of the button back shown mounted upon the stud of the button.

Fig. 4 is a view similar to Fig. 3 with a somewhat modified form of stud and with the parts in a different position.

In proceeding with this invention I provide a resilient washer-like member having an opening therein through which the stud of the button may pass. The stud will be provided with screw threads and if the edges of the opening through which the stud passes flex a substantial amount, the stud may pass through this opening. However, if I control the movement of the edges about the opening to suitably limit their

2

movement, then this stud is prevented from passing through the opening. Thus utilizing this type of control, I provide a plate on one side of the washer-like member locked so closely to

5 the member about the opening that the edges cannot be flexed sufficiently to permit the stud to pass, whereas I provide a plate on the other side of the opening which is arched outwardly from these edges so that these edges may freely 10 flex in this direction and permit the stud to pass through the opening when the edges are flexed in this direction. Thus, I provide an arrangement so that the button back may be forced onto the stud by movement in one direction but 15 which cannot be forced from the stud by movement in the opposite direction.

With reference to the drawings, 10 designates a button having an ornamental face 11, and which is provided with a stud 12 having screw 20 threads 13 along its surface.

The button back consists of a resilient rubber-like washer member 14 which may be formed of rubber, neoprene, or some synthetic plastic having substantially the properties of these materials which will be elastically resilient sufficiently to return to the position from which it has been deformed. This member 14 is provided with a substantially central opening 15 which is of a size a little smaller than the stud 12 so as to 25 grip the same. The serrations or threads 13 on the stud will prevent the sliding of the member 14 therealong but if the edges 16 of the opening 15 are flexed in one direction such as shown in Fig. 3, then the opening 15 becomes sufficiently large so as to permit the stud 12 to pass therethrough. This will occur when the button 30 stud is forced in the direction of the arrow 17 or the button back forced in the direction of the arrow 18.

40 The button back 20 comprises a washer 14 which has a casing provided about it. This casing consists of a flat plate 21 having an opening sufficiently large to permit passage of the stud 12 and the plate is offset as at 22 to provide a recess 45 23 in its edge peripherally thereabout. The other member of the casing is designated 24 and consists of a plate which is arched outwardly as at 25 as shown in Figs. 3 and 4 but which is rolled over as at 26 into the recess 23 so as to bind the edge 50 of the washer member 14 between it and the plate 21. An opening may or may not be provided as at 27 so as to receive the stud therethrough. The outwardly arched portion 25 of this plate 24 is so spaced as to permit the free 55 flexing of the edges 16 of the rubber-like washer

in this direction. The plate 21 is so closely adjacent to the washer 14 as shown in Fig. 4 that the edges are engaged if attempted to be flexed in this direction and thus they cannot flex sufficiently to permit the stud to pass through them such as might occur by reason of relative movement of the parts as shown by the arrows 28 and 29. Thus, in order to detach the parts it would be necessary to relatively rotate them so that a screw action is provided for, whereas for assembly it is merely necessary to force the parts substantially into finished position and then by rotation the screw threads may be brought into play to complete the attaching action. Sufficient resilience is present so that prongs to engage the fabric may be eliminated and thus less hazard of injuring the fabric is present.

The stud 12 may have a square end as shown in Fig. 3 or it may be pointed as in Fig. 4. The threads may be either of the machine screw type as shown in Fig. 3 or of the wood screw type as shown in Fig. 4 or most any other type. These threads, of course, cannot be stripped by the button back used.

I claim:

1. A button back comprising a resilient rubber-like member having an opening therein of a size smaller than portions of a stud to be received therethrough, a first plate on one side of said member engaging the edges thereof but arched away from the member at said opening to permit the edges of the member about the opening to flex into the arched portion sufficiently to pass the stud therethrough and a second plate on the other side of said member having an opening to register with the opening in the rubber member and attached to the first plate at its edges to limit the flexing of the edges of said opening so as to maintain them in engagement with said stud to

bind on the stud whereby the stud may be axially slid in one direction only.

2. A button back as set forth in claim 1 wherein the limiting plate is flat and in substantially one plane.

3. A button back for engaging a screw threaded stud comprising a resilient rubber-like member having an opening therein to receive and grip the threads of the stud, but flexible along the edges of said opening sufficiently to swing outwardly and permit the stud to be pressed therethrough, a first plate on one side of the member engaging the outer edges thereof but arched away from the member at the location of said opening and stud to permit the edges of the opening to be flexed into said arched portion sufficiently to pass said stud and a second plate on the other side of said member having an opening to register with the opening in the rubber member and attached to the first plate at its edges and closely adjacent said member at said opening to engage the edges of said opening and limit the movement of the edges to prevent said stud from sliding therethrough in a direction outwardly of the last said plate, said parts permitting axial movement of the screw threaded studs by relative rotation thereof with reference to said back.
